(57) **CLAIM**

The ornamental design for a display screen or portion thereof with graphical user interface, as shown and described.

DESCRIPTION

FIG. 1 is a front view of a display screen or portion thereof with graphical user interface, showing our new design; and, FIG. 2 is a front view of a display screen or portion thereof with graphical user interface, showing an alternative embodiment of the new design.

The broken lines are for illustrative purpose only and form no part of the claimed design. The dot-dash broken lines define boundaries of the claimed design and form no part thereof. The color of the display screen or portion thereof with graphical user interface forms no part of the claimed design; a display screen or portion thereof with graphical user interface according to the claimed design may be of any color or combination of colors.
